UNITED STATES PATENT OFFICE.

CASSIUS M. SIMPSON, OF CINCINNATI, OHIO.

DISPLAY-BOX.

1,319,973.

Specification of Letters Patent. Patented Oct. 28, 1919.

Application filed May 20, 1919. Serial No. 298,483.

To all whom it may concern:

Be it known that I, CASSIUS M. SIMPSON, a citizen of the United States of America, and a resident of Cincinnati, in the county 5 of Hamilton and State of Ohio, have invented new and useful Improvements in Display-Boxes, of which the following is a specification.

The object of my invention is a box in 10 which articles of merchandise may be packed for shipment and may be placed by the merchant readily in a position to display the merchandise in an attractive manner.

15 This object is attained by the means described in the specification and illustrated in the accompanying drawing, in which:—

Figure 1, is a perspective view of a display box embodying my invention, in its 20 closed position.

Fig. 2, is a perspective view of the cover of my box.

Fig. 3 is a perspective view of the cover.

The box embodying my invention 25 comprises a cover A and a tray B. The cover has a top a , sides a' a'' , one end a^3 and a tray retaining and supporting strip a^4 . The sides a' a'' have their corners a^6 , a^7 , cut at an angle. The tray retaining and supporting strip a^4 forms with the sides a' a'' , the bottom a and the end a^3 , a housing for one 30 end of the tray B, which is of a cross sectional dimension to fit snugly within such housing. Located centrally of the strip a^4 is a longitudinal lug a^5 .

The tray B is of a depth equal to the interior width of the sides a' a'' , and has in its bottom, to one side of the center, a transverse slot b which is of a size to fit snugly 40 over the lug a^5 .

In use when the tray is filled with merchandise for shipment, the cover is slipped over the tray, so that one end thereof fits snugly into the housing formed by the retaining and supporting strip a^4 with the other parts of the cover. When it is desired 45 to remove the tray, the ends thereof are readily grasped because of the cut-away corners a^6 , a^7 of the cover.

In placing the tray in display position, 50 it is rested upon the supporting and retaining strip a^4 , with the lug a^5 engaging slot b . In this position the articles of merchandise are in a position to be easily inspected.

The acts of placing my box in condition 55 for shipment and for putting it in display position, are easily performed. In its display position it has an ornamental appearance and displays the merchandise to good effect.

Moreover because of the one end and the adjacent corner being removed, a good 60 space is left upon the inside of the top of the cover for displaying advertising matter.

Having thus described my invention, what 65 I claim is:—

A display box having a tray and a cover, the cover having a top, side pieces, an end piece and a tray retaining and supporting strip which has a central longitudinal lug 70 and forms with said parts of the box a housing, and a tray which is of dimensions to fit within the cover and having in its bottom, to one side of the center, a transverse slot adapted to engage the lug when 75 the tray is placed in its display position.

In testimony whereof, I have hereunto subscribed my name this 19th day of May, 1919.

CASSIUS M. SIMPSON.
